ADJUSTABLE AXLETREE FOR MOBILE ARTILLERY.

1,163,019.

Specification of Letters Patent.

Patented Dec. 7, 1915.

Application filed January 27, 1913. Serial No. 744,425.

To all whom it may concern:

Be it known that I, NORBERT KOCH, residing at Essen-Rellinghausen, Germany, a subject of the Emperor of Germany, have invented a certain new and useful Improvement in Adjustable Axletrees for Mobile Artillery, of which, the following is a specification.

The present invention relates to a device for eliminating the influence on the direction of firing of the inclined position of the carriage wheels in mobile artillery.

One embodiment of the invention is illustrated in the drawings in its application to a gun mount, wherein the carriage body is displaceable on an axle-tree for laying the gun in side direction, and wherein—

Figure 1 is a side view of the gun mount partly in section and with one of the carriage wheels left out; Fig. 2 a front view of the mount partly in section corresponding to Fig. 1; Fig. 3 a view corresponding to Fig. 2 with the carriage wheels in inclined position; Fig. 4 a section on line 4—4 of Fig. 2; Fig. 5 a detail view partly in section and in larger scale and Fig. 6 a section on the line 6—6 of Fig. 5.

The gun A is carried by the cradle B which rests with its horizontal trunnion b¹ in the carriage body C. Between the cradle B and the carriage body C is inserted an elevating gear comprising a toothed segment, and which toothed segment is designated by D and the hand wheel by d¹. At the rear end of the carriage body is revolvably mounted a spade N by means of a vertical bolt n¹, see Fig. 1.

At the muzzle end of the gun carriage C is situated a guiding piece c¹. The carriage body is by means of this guiding piece guided on a rail e⁶, see Figs. 2, 3 and 4, which is curved concentric to the axis of the spade bolt n¹ and mounted on the middle part E of the axle-tree E, E¹ in such a manner that the training of the gun may be effected by displacing the carriage body on the axle-tree. The training gear is inserted between the carriage body C and the part E of the axle-tree. The training gear comprises a worm G, see Fig. 4 which is carried in bearings in the carriage body, and which worm is in mesh with the worm teeth e⁷ provided on the rail e⁶ and may be turned by a hand wheel G¹.

The axle-tree of the gun carriage consists

of a middle portion E and two cranked axle shanks E¹ which carry the carriage wheels F. The middle portion E may be swung relative to the cranked axle-shanks E¹ around an axis situated in the elevating plane of the gun, that means in a plane running at right angles to the axis of the horizontal trunnions b¹. The outer ends of the middle portion E of the axle-tree, and the inner ends of the axle shanks E¹ are for this purpose provided with sector-shaped projections e² e³ and which engage with each other in the manner shown in Fig. 6 like closed prismatic guides (dove-tail guides). In each of the projections e² of the axle shanks E¹ is mounted a worm H which is in mesh with the worm teeth e⁴, see Figs. 5 and 6, of the corresponding projection e².

A hand wheel M serves to turn the worms H, which hand wheel is mounted on a shaft of one of the worms and which stands in gearing connection with the shaft h¹ of the other worm by means of two pairs of bevel wheels K and K¹ and a shaft L. This shaft L and the ends of the shaft h¹ which carry the bevel wheels K are carried in bearings provided in the arms e⁵ of the projections e³.

In case the gun carriage stands with inclined wheels on the ground, the middle portion E of the axle-tree E, E¹ is then turned by means of the hand wheel M relative to the carriage wheels F into a position in which the axis of the trunnions b¹ will be laid horizontally. The influence on the direction of firing of the inclined position of the carriage wheels, is in this manner entirely eliminated from every elevation and every training of the gun.

Claims:

1. A traveling gun carriage comprising a carriage body adapted to bear on the ground, a wheel axle comprising a pair of axle arms movably mounted on the carriage body and wheels thereon, a gun barrel, a cradle for the gun barrel, horizontal trunnions allowing elevation of the gun barrel relatively to the carriage body, and means between said carriage body and said axle arms allowing said carriage body to swing around a longitudinal axis relatively to said wheels.

2. A gun carriage with an adjustable axle-tree, said axle-tree comprising a middle portion, and a pair of axle shanks forming the axle arms for the carriage wheels, said

middle portion being immovably connected with the gun carriage in a transverse vertical plane, and said middle portion being adjustable relative to said axle-shanks in said vertical plane.

3. A gun carriage with an adjustable axle-tree, said axle-tree comprising a middle portion, and a pair of axle shanks forming the axle arms for the carriage wheels, said middle portion being immovably connected with the gun carriage in a transverse vertical plane, arcuate guides at the free ends of said middle portion, concentrically curved around a horizontal longitudinal axis, a corresponding slide engaging respectively with said guides at the inner end of each of said shanks, and means for simultaneously moving said middle portion relatively to said axle shanks.

20 4. A gun carriage with an adjustable axle-tree, said axle-tree comprising a middle portion and a pair of axle shanks forming the axle arms for the carriage wheels, said middle portion being immovably connected with the gun carriage in a transverse vertical plane, arcuate guides at the free ends of said middle portion concentrically curved around a horizontal longitudinal axis, a corresponding slide engaging respectively with said guides at the inner end of each of said

axle shanks, and means for moving said middle portion relatively to said axle shanks; said means comprising a worm in each of said slides and a toothed gearing connection.

35

5. A gun carriage with an adjustable axle-tree, said axle-tree comprising a middle portion, and a pair of axle shanks forming the axle arms for the carriage wheels, said middle portion being immovably connected with the gun carriage in a transverse vertical plane, arcuate guides at the free ends of said middle portion and concentrically curved around a horizontal longitudinal axis, a corresponding slide engaging respectively with said guides at the inner end of each of said axle shanks, and means for moving said middle portion relatively to said axle shanks; said means comprising a worm in each of said slides and a toothed gearing connection whereby the gun trunnions may be retained horizontally both in elevation and training of the gun.
